(57) **CLAIM**

I claim the ornamental design for a display rack, as shown and described.

DESCRIPTION

FIG. 1 is a side elevation of a display rack of the present invention, the other three sides being identical thereto.

FIG. 2 is a top elevation view of the display rack shown in the previous figure.

FIG. 3 is a bottom elevation view of the display rack shown in the previous figures; and,

FIG. 4 is a perspective view of the display rack from the upper left of FIG. 1.

The broken lines are intended to illustrate a series of hooks situated on the underside of the outwardly extending arms of the display rack. The hooks shown in the drawings are for illustrative purposes only and form no part of the claimed design.
